US0D1113084S

(12) **United States Design Patent** (10) **Patent No.:** **US D1,113,084 S**
(45) **Date of Patent:** **** Feb. 17, 2026**

(54) **HEADBAND SUPPORT**

(71) Applicant: **Vuzix Corporation**, West Henrietta, NY (US)

(72) Inventor: **Erik Zelbacher**, Pittsford, NY (US)

(73) Assignee: **Vuzix Corporation**, West Henrietta, NY (US)

(**) Term: **15 Years**

(21) Appl. No.: **29/904,478**

(22) Filed: **Oct. 6, 2023**

(51) LOC (15) Cl. **02-03**

(52) U.S. Cl.

USPC **D2/891**

(58) **Field of Classification Search**

USPC D2/865, 866, 869, 871, 872, 873, 874, D2/875, 876, 877, 879, 882, 884, 885, D2/886, 887, 891, 892, 893, 894

CPC A42B 1/00; A42B 1/002; A42B 1/004; A42B 1/006; A42B 1/008; A42B 1/018; A42B 1/0181; A42B 1/0182; A42B 1/02; A42B 1/14; A42B 1/205; A42B 7/00; A42C 5/00; A42C 5/02; A42C 5/04

(57) **CLAIM**

The ornamental design for a headband support as shown and described.

DESCRIPTION

FIG. 1 is a top, front, right-side perspective view of a new and ornamental design for a headband support.

FIG. 2 is a right-side elevation view thereof.

FIG. 3 is a left-side elevation view thereof.

FIG. 4 is a top plan view thereof.

FIG. 5 is a bottom plan view thereof.

FIG. 6 is a front elevation view thereof.

FIG. 7 is a rear elevation view thereof; and,

FIG. 8 is a bottom, rear, left-side perspective view thereof. Broken lines in the figures illustrate portions of the headband support that form no part of the claimed design.

1 Claim, 8 Drawing Sheets
